[57] CLAIM

The ornamental design for a pneumatic hand tool, as shown and described.

DESCRIPTION

FIG. 1 is a left side elevational view of the pneumatic hand tool of my new design, the portions shown in phantom forming no part of the design, the right side elevational view being a mirror image of the left side;

FIG. 2 is a bottom plan view thereof;

FIG. 3 is a top plan view thereof;

FIG. 4 is a rear elevational view thereof;

FIG. 5 is a front elevational view thereof;

FIG. 6 is a left side elevational view of a second embodiment of the pneumatic hand tool of my new design, the portions shown in phantom forming no part of the design, the right side elevational view being a mirror image of the left side and the bottom, top, rear, and front views being like FIGS. 2, 3, 4, and 5, respectively; and,

FIG. 7 is a left side elevational view of a third embodiment of the pneumatic hand tool of my new design, the portions shown in phantom forming no part of the design, the right side elevational view being a mirror image of the left side and the bottom, top, rear, and front views being like FIGS. 2, 3, 4, and 5, respectively.
